UNITED STATES PATENT OFFICE.

ANNIE M. CORDLEY, OF GLENRIDGE, NEW JERSEY.

SURGICAL APPLIANCE AND METHOD OF FORMING THE SAME.

No. 920,112.

Specification of Letters Patent.

Patented May 4, 1909.

Application filed March 14, 1908. Serial No. 421,015.

To all whom it may concern:

Be it known that I, ANNIE M. CORDLEY, a citizen of the United States, residing in Glenridge, in the State of New Jersey, have invented certain new and useful Improvements in Surgical Appliances and Methods of Forming the Same, of which the following is a specification, reference being had to the accompanying drawing, forming a part hereof.

10 It frequently becomes necessary, in the event of injury to any part of the body or of disease which attacks locally some part of the body, to provide a rigid support for the affected part of the body, either for the purpose of affording comfort or of promoting the restoration of affected tissues to normal condition. Various expedients have been resorted to for the general purpose indicated. Thus, a textile fabric, saturated with a stiffening solution or mixture, has been conformed, while wet, to the part of the body to be supported and has then been allowed to dry and harden. Such a support has the proper shape provided it is not lost before the 25 supporter becomes dry and hard, and it has also the desirable quality of lightness, but it is not sufficiently stiff and unyielding for all purposes. Where an absolutely rigid support is required as, for example, for the arch 30 of the foot, a metal plate has been hammered to approximately the desired shape, and metal plates are also stamped or molded by machinery. The latter, that is, the plates stamped or molded by machinery, do not, 35 except as a matter of accident, conform so closely to the normal shape of the individual foot as to permit their use for surgical purposes, and the former, that is, the plate hammered by a skilful artisan to conform to the 40 individual foot, may answer the purpose in some cases, so far as the surgical requirements are concerned, but it usually falls so far short of the exact conformation as to cause great discomfort to the user.

45 It is the object of this invention to provide a support which, by reason of its exact conformation and the nature of the material of which it is composed, shall overcome the difficulties and objections above enumerated, 50 being capable of being worn without discomfort and of furnishing an absolutely rigid support when such a support is necessary.

The invention is more particularly described hereinafter with reference to its embodiment in a support for the foot and in the

method of forming such a support, and in the accompanying drawing, which is merely illustrative of the general nature of the invention, Figure 1 is a top view of a foot support which embodies the invention. Fig. 2 is an 60 underside view of the same, and Fig. 3 is a transverse section.

In practicing the invention, so far as it resides in the method, and in producing the support which also embodies the method, a 65 cast of the foot or other part of the body is first formed in any convenient manner, as by first forming a mold of plaster of paris or other suitable material of the part of the body to be supported and then making a cast 70 therefrom, preferably in plaster of paris, so that the cast presents the exact conformation of the part of the body to be supported. The cast is then suitably prepared, as by coating it with black lead and the support is 75 formed thereon by electro-deposition in the usual and well known manner. Any suitable metal, which is readily capable of electro-deposition, may be used for the purpose and the electro-deposition thereof is 80 continued until a support of substantial thickness and rigidity is formed. Such a support is shown as *a* in the drawing, and it will be obvious that such support, so formed upon a 85 cast of the foot, will conform precisely to the natural conformation of the foot and is not liable to change after being removed from the cast. Moreover, as will be obvious, the support is of substantial thickness and is, 90 therefore, capable of being used without discomfort, even between the sole of the foot and the sole of the shoe. As is well understood, however, most metals which lend themselves most readily to electro-deposition are not only relatively soft but become 95 spongy when the electro-deposition continues beyond a limited thickness. In some cases, therefore, the support formed by electro-deposition only has not sufficient 100 strength to properly support the part of the body for which it is intended. This is particularly true in the case of a support for the arch of the foot. It is therefore sometimes necessary to reinforce and stiffen the electro-deposited support by securing to the outer 105 surface thereof reinforcing or stiffening strips *b* of a metal stiffer than that which can be employed to advantage in electro-deposition. These reinforcing and stiffening strips may be riveted to the electro-deposited 110

shell *a*, as indicated at *c*, but they are preferably formed of such metal as to permit them to be secured to the shell *a* throughout their length, as by solder, as indicated at *d*. The 5 number and position of such stiffening strips will depend upon the requirements of each case.

The supporter, formed as described, combines the maximum of comfort for the user 10 with the degree of stiffness required by the surgical conditions.

I claim as my invention:

1. The method of forming a support for a portion of the body which consists in forming 15 a mold of the portion of the body to be supported, taking a cast from said mold, preparing the surface of the cast for electro-deposition of metal thereon, electrically depositing a layer of metal on such cast to a 20 substantial thickness, and reinforcing the layer of metal thus produced by securing a

piece of relatively stiffer metal to the surface of said layer.

2. A support for a portion of the body comprising an electro-deposited shell conforming to the portion of the body to be supported and a reinforcing strip of relatively stiffer metal secured to the outer surface thereof. 25

3. A support for a portion of the body 30 comprising an electro-deposited shell conforming to the portion of the body to be supported and a reinforcing strip of relatively stiffer metal soldered throughout its length to the outer surface of the electro-deposited 35 shell.

This specification signed and witnessed this fourth day of March, A. D., 1908.

ANNIE M. CORDLEY.
